UNITED STATES PATENT OFFICE

165,583

TWIN WINDOW FAN

Benjamin H. Johnson, Mason, and William W. Welch, Jr., Cincinnati, Ohio, assignors to William W. Welch, Cincinnati, Ohio

Application April 7, 1950, Serial No. 9,041

Term of patent 14 years

(Cl. D62—4)

To all whom it may concern:

Be it known that we, Benjamin H. Johnson and William W. Welch, Jr., citizens of the United States of America, and residents of Mason, in the county of Warren and State of Ohio, and Cincinnati, in the county of Hamilton and State of Ohio, have invented a new, original, and ornamental Design for a Twin Window Fan, of which the following is a specification, reference being had to the accompanying drawings, forming a part hereof:

Fig. 1 is a front perspective view of a twin window fan embodying our new design;

Fig. 2 is a top plan view thereof; and

Fig. 3 is a front elevational view thereof.

The end, bottom and back, not shown by the drawings, are substantially plain.

We claim:

The ornamental design for a twin window fan, as shown and described.

BENJAMIN H. JOHNSON.
WILLIAM W. WELCH, JR.
